UNITED STATES PATENT OFFICE.

HARRISON ARMS, OF TOLEDO, OHIO.

STOCK-CAR.

SPECIFICATION forming part of Letters Patent No. 328,746, dated October 20, 1885.

Application filed July 20, 1885. Serial No. 172,048. (No model.)

To all whom it may concern:

Be it known that I, HARRISON ARMS, of Toledo, in the county of Lucas and State of Ohio, have invented certain new and useful 5 Improvements in Stock-Cars, of which the following is a specification, reference being had to the accompanying drawings, and to the letters of reference marked thereon.

This invention has reference to an improvement upon the invention described in Letters Patent No. 308,808, issued to me, and is designed to simplify and increase the efficiency of certain features of the invention therein claimed.

15 The present invention has reference, particularly, to the partition between the stalls.

In the accompanying drawings, Figure 1 is a side elevation of a part of a partition and its adjuncts. Fig. 2 is a vertical section. Fig. 20 3 is a view of a detail.

Similar letters of reference indicate similar parts in the respective figures.

A is one of the posts to which the partition is hinged.

25 B is the hinging pin or bolt. The lower end of the pin or bolt B is dropped into a hollow casting, L, which is bolted to the lower end of the post A. The upper end of the pin B is flattened and bolted to the post A.

30 C is the partition mounted upon hinges a, which run and turn upon the bolt B.

H is a casting upon which the lower and outer corner of the partition rests when in place, as shown in Figs. 1 and 2. In the latter figure the casting H is shown L-shaped.

J is a casting similar to that H, both castings being bolted to the side of the car.

I is a latch or bar pivoted to the partition C at b, and capable of vertical movement on its pivot.

40 K is a casting pivoted to the side of the car at b', and capable of lateral movement upon its pivot, as shown in dotted lines in Fig. 3. This casting K, when hanging perpendicularly, prevents the partition from being jolted or otherwise moved out of its position.

45 When it is desired to swing the partition upon its hinging-bolt B, the casting K is swung to the position shown in dotted lines in Fig. 2, and the latch I lifted. The partition must now be lifted upon its hinging-bolt B 50 clear of the casting H and swung to the necessary position.

Having described my invention, I claim—

1. In a stock-car, the combination of the 55 partition C and castings H and J, substantially as and for the purpose described.

2. In a stock-car, the combination of the partition C, castings H and J, and latch I, substantially as and for the purpose specified. 60

3. In a stock-car, the partition C, hinged to the bolt or pin B, combined with castings H and J, latch I, and pivoted casting K, all substantially as and for the purpose specified.

65 In testimony whereof I hereunto set my hand and seal.

HARRISON ARMS. [L. S.]
